(57) **CLAIM**

The ornamental design for a vehicle lamp reflector with an applied pattern of reflected lights, as shown and described.

DESCRIPTION

The sole FIGURE is a view of a vehicle lamp reflector with an applied pattern of reflected lights showing my new design. The pattern of light is centered around a central perpendicular axis. The broken line showing of a front portion of a lamp reflector and a central source of the reflected light are included for illustrative environmental purposes only and form no part of the claimed design.
